CLAIM

The ornamental design for a wastebasket, as shown and described.

DESCRIPTION

FIG. 1 is a perspective view of a wastebasket showing my design;

FIG. 2 is a front elevational view thereof;

FIG. 3 is a rear elevational view thereof;

FIG. 4 is a left elevational view thereof, with the right elevational view being a mirror image;

FIG. 5 is a top plan view thereof;

FIG. 6 is a bottom plan view thereof; and,

FIG. 7 is another perspective view of the wastebasket, shown in an open state.

The broken lines in the drawings depict portions of the wastebasket that form no part of the claimed design.
